UNITED STATES PATENT OFFICE

1,988,370

AUTOMATIC VOLUME CONTROL

Reynolds D. Brown, Jr., Philadelphia, Pa., assignor to Philadelphia Storage Battery Company, Philadelphia, Pa., a corporation of Pennsylvania

Application December 6, 1929, Serial No. 412,163

6 Claims. (Cl. 250—20)

This invention relates to radio receiving systems and has particular reference to automatically maintaining the volume output level of such systems constant in spite of the variations of the input carrier wave voltage and is a modification of the system described in a co-pending application, Serial No. 405,964, filed November 9, 1929, by D. G. McCaa and myself. It includes the features of the co-pending application plus the double use of a volume control amplifier either as an audio frequency or a radio frequency amplifier in addition to its use as a direct current amplifier. The principal object of the invention is to provide a receiving system in which the output volume is maintained at a predetermined level in spite of any increase or decrease in the input carrier voltage which may be due to variation of field strength at the antenna caused by varying distances or variations in power of the transmitting stations or due to fading.

Another object is to so control the output volume of a radio receiving system that strong carrier waves are reduced to a predetermined level, while carrier waves, which are weaker than that level, will be totally unaffected. In other words, unless the carrier wave is present and is higher than the level setting, the radio receiving system will be maintained at its normal sensitivity.

A further object is to provide a more sensitive control than has heretofore been possible with systems of the prior art and which is obtained by deriving a direct current voltage from the system, amplifying this voltage and then using the amplified voltage to bias the grid or grids of one or more tubes of the system.

Another object of the invention is to provide a sensitive automatic volume control which, when incorporated with a receiving system, will function without producing howls due to the setting up of local oscillations or the feeding back of undesirable oscillations from the system into the direct current amplifier.

A still further object of the invention is to provide a direct current amplifier for amplifying the derived direct current voltages which may be used additionally as an amplifier of either radio or audio frequency currents.

The biasing voltage may be derived from the output of the detector tube, as shown in one modification or it may be derived from any tube other than the detector, as may be desired.

Some of the features of the voltage control

of the present invention which distinguish it from the prior art are:

(1) The provision of a special radio frequency filter in the grid circuit in the tube or tubes which are automatically biased and the provision of other filters in the system which make for the difference between satisfactory operation of the system and a system which would set up undue howls caused by local oscillations being generated.

(2) The use of a high impedance primary coil in the output circuit of the automatically biased tube or tubes for reasons which will appear hereinafter.

(3) The use of a direct current amplifier to increase the effect of the biasing voltage derived from the system.

(4) The provision of an automatic biasing means on the detector itself.

(5) The use of a level-adjusting resistance between the automatic biasing means in the plate circuit of the detector and the grid or grids of the direct current amplifier instead of using a voltage divider in the audio output circuit.

A clear understanding of the description and operation of the system will be had from the drawing, in which the single figure is a wiring diagram of a radio receiving system with the modifications and additional apparatus required to carry out my invention with the use of a grid bias detector.

Referring to Fig. 1, the vacuum tubes V_1 and V_2 are radio frequency amplifying tubes which are connected in cascade by means of transformer T_1 and the antenna circuit is coupled to the tube V_1 by means of the transformer T . Following the tube V_2 is a detector tube V_3 of the grid bias type which is coupled to tube V_2 by means of transformer T_2 and has its output coupled to the tubes V_4 and V_5 by means of transformer T_3 . Tubes V_4 and V_5 are coupled to an output circuit by means of transformer T_4 . All of the tubes of the system shown are of the heater type and the heating current is derived from an alternating current source, but it is obvious that the filament type of tubes may be used. Tube V_2 may be of the screen grid type. Tubes V_4 and V_5 are arranged in push-pull relation having their grids and plates connected together by means of coils S_3 and P_4 , respectively. The tubes are arranged in push-pull relation only with respect to the audio frequency currents introduced therein by means of transformer T_3 and are arranged to operate in parallel relation in amplifying the direct current voltages derived from

the detector tube V_3 .

The circuit of the system is as follows: The antenna circuit is connected to the grid of tube V_1 through the transformer T . The plate circuit of tube V_1 is connected to the grid of tube V_2 through the transformer T_1 . The plate circuit of tube V_2 is connected to the grid of tube V_3 through the transformer T_2 . The plate circuit of tube V_3 is connected to the grids of tubes V_4 and V_5 through the transformer T_3 . The plate circuit of tubes V_4 and V_5 is connected to the output circuit through the transformer T_4 .

The filament of tube V_2 is connected to a filament transformer F_2 which is connected to an alternating current source. The filament of tube V_3 is connected to a filament transformer F_3 which is connected to an alternating current source. The filaments of tubes V_4 and V_5 are connected to a filament transformer F_4 which is connected to an alternating current source.

The filament of tube V_1 is connected to a filament transformer F_1 which is connected to an alternating current source. The filament of tube V_2 is connected to a filament transformer F_2 which is connected to an alternating current source. The filament of tube V_3 is connected to a filament transformer F_3 which is connected to an alternating current source. The filaments of tubes V_4 and V_5 are connected to a filament transformer F_4 which is connected to an alternating current source.

the output of the detector V_3 . The tuned circuits of tubes V_1 , V_2 and V_3 are adjusted by the variable condensers VC which are arranged to be adjusted simultaneously. In order to prevent self-oscillation of this system, the tube V_1 is neutralized by means of condenser C_8 and in order to prevent undesirable oscillations from being fed back from the output circuits of tubes V_4 and V_5 into the direct current amplifier, and into grid-cathode circuits of tubes V_1 and V_2 , special filters are provided comprising radio frequency choke coils RFC and condensers C_1 , C_2 and C_3 . The condensers VC are connected to ground and the output circuit of the tube V_1 is provided with a radio frequency by-pass condenser C_4 and a choke resistance R_6 . A similar condenser and resistance C_5 and R_3 are provided in the screen grid circuit of tube V_2 . In the plate circuit of detector tube V_3 are a radio frequency choke RFC , a radio frequency by-pass condenser C_7 and an audio frequency by-pass condenser C_6 . The special filters and all of the various by-passes add to the satisfactory operation of the system. The detector tube V_3 is provided with an automatic biasing means comprising resistance R and condenser C connected in parallel with each other and placed in series with the plate cathode circuit of the tube. The point x , which is the lower end of the secondary S_2 may be connected to ground, as indicated in the diagram, or it may be connected to the upper terminal of the time circuit (RC) or to any other point of appropriate direct current potential. The positive end of the RC circuit, which is indicated in the drawing as the upper end, is connected to one end of a potentiometer r_1 . The tap y of potentiometer r_1 is connected to the center tap of the secondary S_3 of the transformer T_3 , the terminals of which are connected to the grids of tubes V_4 and V_5 . The other terminal of potentiometer r_1 is connected to a positive potential of 20 volts. The cathodes of tubes V_4 and V_5 are connected to a point z which may be connected to a positive potential of 70 volts. The primary P_4 , which connects the plates of the tubes V_4 and V_5 , is provided with a center tap which is connected through another time circuit $R'C'$ to a source of direct current potential of such magnitude as required by the anodes of the tubes V_4 and V_5 . The upper terminal of the time circuit $R'C'$, which is designated as being negative, is connected back to the grid circuit of tube V_1 and through the resistance r_4 to resistance r_5 and the grid circuit of tube V_2 . The resistances r_4 and r_5 are provided to produce different degrees of automatic grid bias on the tubes V_1 and V_2 . The ratio of resistance r_4 to r_5 may be of the order of 4 to 1, that is, the value of automatic bias on the grid of tube V_1 is four times that of the bias on tube V_2 . The plates of the tubes V_1 , V_2 and V_3 are supplied with appropriate positive potentials, as indicated. The potentiometer r_1 is used to adjust the carrier output level to any predetermined value and when its variable tap is moved to the upper end of the resistance, full carrier volume control occurs and when moved to the lower end of the resistance R_1 , no carrier volume control occurs. The direct current biasing potential, which is derived from the plate-cathode circuit of the detector V_3 , is applied from points y , z to the grids and cathodes of the tubes V_4 and V_5 , respectively, the point y being negative with respect to point z .

75. The primary P_2 in the output circuit of the

tube V_2 comprises, for example, sixty turns instead of the usual fifteen turns and provides a high impedance in the output circuit to match the internal impedance of the tube V_2 . By providing a high impedance primary of the transformer T_2 , maximum amplification is obtained with a higher bias voltage on the grid of tube V_2 than when a standard transformer is used in which maximum amplification occurs at a much lower grid bias. It is, therefore, apparent that with a high impedance primary, a lower negative voltage is required on the grid of tube V_2 to cut off the signal.

The operation of the system is as follows:— when there is no carrier present, no current flows in r_1 because the upper terminal of circuit RC is at a positive potential of 20 volts and the other end of r_1 is connected to a positive potential of 20 volts. When a carrier is present and the carrier voltage increases, the plate current in the detector tube increases and the upper terminal of the RC circuit becomes more positive or less negative, thereby making the grid of the detector more negative and the grids of the push-pull tubes V_4 and V_5 less negative and allowing more plate current to flow through the circuit $R'C'$ and causing an increased negative voltage to be impressed on the grids of tubes V_1 and V_2 from the upper terminal $R'C'$. The adjustment of the carrier level by means of the potentiometer r_1 has no direct effect on the audio frequency signal level. It will be seen that when the carrier voltage increases, it immediately produces a direct current voltage across the points y , z which is impressed on the grids of tubes V_4 and V_5 where it is amplified and causes an increased current to flow through circuit $R'C'$, whereby an increased potential drop is produced and is applied to the grids of the tubes V_1 and V_2 which causes a reduction of amplification in these tubes and restores the carrier output to the level for which the system is adjusted. As hereinbefore stated, the tubes V_4 and V_5 act in parallel relation as direct current amplifiers since the grids are at the same potentials simultaneously and their outputs are connected so that the plate currents from the two tubes are additive in their effect on the circuit $R'C'$. However, for audio frequency signal currents, the tubes V_4 and V_5 act in "push-pull" relation since the grid of one tube is positive, while the grid of the other tube is negative and vice versa.

When the tubes V_4 and V_5 are biased to the normal value for "push-pull" action, there is no change in the total plate current of the tubes due to audio frequency currents and, therefore, there is no effect on $R'C'$ except that due to the bias voltage derived from the circuit RC .

While I have shown only one form of embodiment of my invention, for the purpose of description and illustration of its principles of construction and operation, it is apparent that various changes and modifications may be made therein without departing from the scope of the invention. I desire, therefore, that only such limitations shall be imposed thereon as are indicated in the appended claims or as are demanded by the prior art.

I claim:

1. In a carrier wave receiving system comprising a plurality of carrier frequency amplifying tubes, a detector and audio frequency amplifying tubes in "push-pull" relation, the method of automatically controlling the carrier output

level which comprises deriving a uni-directional voltage from the plate circuit of said "push-pull" tubes, the value of said voltage depending on the carrier voltage, and causing said derived voltage to affect one or more of the carrier frequency amplifying tubes, thereby reducing the efficiency of the system in accordance with the carrier amplitude.

2. In a carrier wave receiving system including a plurality of vacuum tubes, one of said tubes having a higher amplification factor than another of said tubes, the method of automatically controlling the output level of said system comprising deriving a uni-directional current from said system, passing said current through a divided resistor to produce a plurality of voltages, and applying one of said voltages to the grid of the lower amplification tube and the lesser of said voltages to the grid of the higher amplification tube, whereby their efficiencies are modified to substantially the same extent.

3. In a carrier wave receiving system comprising a plurality of carrier frequency amplifying tubes, a detector and audio frequency amplifying tubes in "push-pull" relation, the method of automatically controlling the signal output level which comprises deriving a uni-directional voltage from the plate circuit of said "push-pull" tubes, the value of said voltage depending on the signal voltage, and causing said derived voltage to affect one or more of the carrier frequency amplifying tubes, thereby reducing the efficiency of the system in accordance with the signal amplitude.

4. In a carrier wave receiving system comprising a plurality of carrier frequency amplifying tubes, a detector, and audio frequency amplifying tubes in "push-pull" relation, means for automatically controlling the signal output level of the system comprising means for deriving a uni-directional voltage from the plate circuit of

said "push-pull" tubes, the value of said voltage depending upon the signal voltage, and means for causing said derived voltage to effect one or more of the carrier frequency amplifying tubes, thereby reducing the efficiency of the system in accordance with the signal amplitude.

6. In a carrier wave receiving system comprising a plurality of carrier frequency amplifying tubes, a detector, and audio frequency amplifying tubes in "push-pull" relation, the method of automatically controlling the signal output level which comprises deriving a uni-directional voltage from the circuit of the detector, the value of said voltage depending on the signal voltage, applying said voltage in parallel to the input of said "push-pull" tubes, deriving a second uni-directional voltage from the plate circuit of said "push-pull" tubes, and causing said second uni-directional voltage to effect one or more of the carrier frequency amplifying tubes, thereby reducing the efficiency of the system in accordance with the signal amplitude.

6. In a carrier wave receiving system comprising a plurality of carrier frequency amplifying tubes, a detector, and audio frequency amplifying tubes in "push-pull" relation, means for automatically controlling the signal output level, comprising means for deriving a uni-directional voltage from the circuit of the detector, the value of said voltage depending on the signal voltage, means for applying said uni-directional voltage in parallel to the input of said "push-pull" tubes, means for deriving a second uni-directional voltage from the plate circuit of said "push-pull" tubes, and means for causing said second uni-directional voltage to effect one or more of the carrier frequency amplifying tubes, thereby reducing the efficiency of the system in accordance with the signal amplitude.
